(57) **CLAIM**

The ornamental design for a handbag, as shown and described.

DESCRIPTION

1.1 is a perspective view of a handbag, showing my new design;

1.2 is a front view thereof;

1.3 is a back view thereof;

1.4 is a right view thereof;

1.5 is a left view thereof;

1.6 is a top view thereof; and

1.7 is a bottom view thereof.

The broken lines in the reproductions represent seams and form no part of the claimed design. The floral crescent elements represent surface indicia.
